UNITED STATES PATENT OFFICE.

CHRISTOPHER ZICKLER, OF PITTSFIELD, MASSACHUSETTS.

LAWN-MOWER.

SPECIFICATION forming part of Letters Patent No. 716,164, dated December 16, 1902.

Application filed June 24, 1902. Serial No. 112,967. (No model.)

To all whom it may concern:

Be it known that I, CHRISTOPHER ZICKLER, a citizen of the United States of America, and a resident of Pittsfield, in the county of Berkshire and State of Massachusetts, have invented certain new and useful Improvements in Lawn-Mowers, of which the following is a full, clear, and exact description.

This invention relates to improvements in lawn-mowers of the class in which there is comprised in the machine a reciprocating cutter-bar, the movement of which is produced from the rotation of the traction-roller of the machine.

15 The features of improvement particularly consist in specific arrangements of the driving-gearing and ball-bearings therefor and means for adjusting the bearings, means of adjustment of the cutter-bar support relatively to the cutter-bar, (the cutter-bar may work with all required freedom and yet with sufficient closeness and accuracy for best results,) and generally to improved and specific devices, as will hereinafter appear, and 25 be set forth in the claims.

Reference is to be had to the accompanying drawings, in which—

Figure 1 is a partial horizontal sectional and partial plan view of the improved lawn-mower. 30 Fig. 2 is a vertical sectional view on line 2 2, Fig. 1. Fig. 3 is a vertical sectional view in detail on line 3 3, Fig. 1. Fig. 4 is a side view of the pitman-rod employed in the driving connection.

35 Similar characters of reference indicate corresponding parts in all of the views.

In the drawings, A A represent the side members of the machine-frame, transversely united by the fixed shaft B and the normally 40 stationary bar C at the forward portion of the frame, which latter bar constitutes the base member on and with which the cutter-bar E cooperates.

The cutter-bar has at its ends the narrowed 45 extensions a a, which play through apertures b b in the side members, the walls of said apertures serving as guides for the said cutter-bar extensions.

The traction-roller D rotates about the fixed 50 shaft B, ball-bearings being interposed be-

tween the said shaft and the hubs d d of the traction-roller, which are loose relatively to the shaft.

The spokes e e, which unite the roller and its hubs, are constituted by screw-rods, the 55 inner extremities of which are threaded and screw-engaged in threaded radial sockets in the hubs, the heads or enlargements e² being seated in outwardly-opening countersunk sockets in the roller.

60 The screw-rods have their heads slotted, so that by individually turning the rods the central hubs may be brought to adjustment in axial alinement within the roller.

The outer end portions of the hubs have 65 comparatively deep cup-shaped sockets f to constitute raceways for the balls g, which are comprised between the internal surfaces within the hubs and the cones h h².

The one end cone h² screw-engages the correspondingly-threaded extremity h³ of the shaft B and is adjustable in the usual way.

70 The cone h is shown as one cone member of a double-cone hub h h' for the gear-wheel i, the outer cone portion h⁴ of which sets somewhat deeply into the socketed part j, which is of corresponding form to the adjacent deeply-socketed hub for the roller. This latter part j is screw-threaded on the end portion h⁵ of the shaft, and its construction and 75 relative arrangement are such that the adjustment for all of the three sets of ball-bearings shown may be effected by rotating the part j, it being understood that the gear-wheel is loose on the shaft B and may have a slight 80 endwise motion along it, as well as a rotatable motion thereon in one direction, the usual provision of ratchet-teeth at k on the hub of the roller and the pawl m, pivotally mounted on the face of the gear-wheel i, preventing 85 the rotational movement of the gear-wheel independently of the shaft when the roller is run forwardly, as common in lawn-mowers, wherein it is required that the forward rolling of the traction-roller will correspondingly 90 rotationally drive the gear-wheel and through intervening mechanism the cutter.

95 l represents a lock-nut for confining the bearings in their adjustment.

The construction of the gear-wheel i with 100

double cone-shaped hubs, one of which sets into the deeply-socketed adjustable ball-race member *j*, conduces to extreme practicability and easy running of the driving mechanism 5 for the cutter, and the deep ball-races enveloping the cones and interposed balls serve as guards for the exclusion of grass and dirt from the bearings.

The cutter-bar, as before mentioned, has at 10 its ends the narrowed extensions *a*, which play with a close yet free fit through the apertures *a a* in the side members *A A*, the cutter-bar being supported upon the normally stationary horizontal transverse bar *C*, and in 15 order to afford the adequate means of guidance to the cutter-bar and stability thereof in its reciprocatory movements the side members *A A* are constructed with the inwardly-extending horizontal lugs or brackets *n n*, 20 which have within their thickness the downwardly-open guideways *n²*. (See Fig. 3.)

As it is desired that the forwardly-extending prongs *o o* of the cutter-bar shall at all times work in the proper shearing proximity 25 to the prongs *p* of the stationary bar *C*, provision is made for the adjustment in a vertical direction of said bar *C*, the same consisting in having at each end portion of the bar the rearwardly-disposed supporting-screw *q*, 30 which passes loosely through a hole in the bar and with a screw engagement upwardly into the bracket *n*, the head of the screw having a supporting-bearing under and against the bar, and the forwardly-disposed screw *r* 35 is similarly applied and, moreover, has a spiral spring *s* surrounding it and interposed between the two bars, so as to react downwardly against the bar *C*, with a tendency to force and maintain it away from the under 40 surface of the cutter-bar and its prongs, and yet permit by the setting up of the duplicated screw *r* the maintenance of the lower bar *C* in its most advantageous position or working relation to the cutter-bar. The rear screws *q q* 45 serve as fulcrums, from which the bar *C* has the slight degree of vertical swinging motion.

The cutter-bar is reciprocated from the forward rotations of the gear-wheel *i* through the shaft *G*, which has the gear-wheel *s* fixed 50 thereon and which meshes into the gear-wheel *i*, and which shaft has the crank member *t* to which the pitman-rod *u* is connected, the latter being by its opposite end connected to the central portion of the cutter-bar.

55 The pitman-rod is shown in Fig. 4 as of a bowed form, whereby to obstruct as little as possible the passage of the clipped grass back of the cutter-bar as the lawn-mower progresses. There is a comparatively large rectangular space between the cutters and the traction-roller, in which may be set a pan or receptacle to catch the clipped grass, the lugs *v v*, which are shown extending inwardly horizontally from the lower portions of the side 60 members *A A*, serving as simple yet practi-

cable means for the support of the grass-receiving pan.

Having thus described my invention, what I claim, and desire to secure by Letters Patent, is—

70 1. In a lawn-mower, a traction-roller comprising the roller proper, the hubs, having screw-tapped radial sockets, and the spokes having threaded inner extremities screw-engaging in said sockets and having slotted 75 heads, setting in countersunk sockets which are provided within the outer surface of the roller.

75 2. In a lawn-mower the combination with the side members *A A* and the fixed shaft *B* 80 having the screw-threaded end portion *h⁵* of the roller having the hubs *d d* provided with the deep ball-race sockets, the cone *h²* and the balls, the gear-wheel *i* having the double-cone-ended hub, one cone member protruding 85 into the adjacent ball-race of the roller-hub, the socketed ball-race member *j* screw-engaging the threaded portion of the shaft and having an inclosing relation to the outwardly-protruding cone-hub of the gear-wheel, the balls between the gear-cones and the adjacent roller-hub and the said part *j*, the lock-nut *l*, the cutter-bar; and driving 90 connections between said gear-wheel and the cutter-bar substantially as described and for 95 the purposes set forth.

3. In a lawn-mower the combination with the side members having the apertures *b b* therethrough and the inwardly-extending brackets *n n* having at their under sides the 100 recesses *n²*, of the normally stationary transverse bar *C* having the cutter members *p*, the cutter-bar *C* having the end extensions *a a* arranged for guidance in said recesses *n²* and to play through said apertures *b*, and having 105 the cutter members *o*, and means for reciprocating the cutter-bar.

4. In a lawn-mower the combination with the side members *A A* having at their forward inner lower portions the brackets *n* constructed with the under side transverse guide-recesses *n²*, and the said side members having the apertures *b*, of the normally stationary horizontal transverse bar *C* the end portions of which are disposed closely under said 110 brackets, the rearwardly-disposed screws *q q* having their heads against the lower surface of the bar and having their shanks extended loosely through the bar and with a screw engagement into the brackets, and the similarly-engaged forwardly-disposed screws *r* and springs *s* applied between the brackets and said bar exerting a downward pressure 115 on the latter, the cutter-bar *E* reciprocating upon said bar *C* and having the end extensions *a a* guided in said recesses *n²* and playing through said apertures *b*, and means for reciprocating the cutter-bar, substantially as 120 and for the purposes set forth.

5. In a lawn-mower, in combination, the bar 125

C and the cutter-bar transversely arranged at the front, and the rearwardly-disposed traction-roller, the side members A A having at their lower inner portions the inwardly-extending lugs v v, and means provided between the traction-roller and the cutter-bar for reciprocating the latter.

Signed by me at Pittsfield, Massachusetts, in the presence of two subscribing witnesses.

CHRISTOPHER ZICKLER.
